UNITED STATES PATENT OFFICE.

MASON SCUDDER, OF ST. LOUIS, MISSOURI, ASSIGNOR TO RAWLINGS MANUFACTURING COMPANY, OF ST. LOUIS, MISSOURI, A CORPORATION OF MISSOURI.

FOOTBALL, BASKET BALL, AND THE LIKE.

Application filed March 8, 1926. Serial No. 93,143.

This invention relates to foot balls, basket balls and similar balls of the type in which the bladder is equipped with an inflating valve whose stem is so arranged that a pump 5 can be connected to same without disturbing the lacing that closes the slit in the casing through which the bladder is inserted in the casing.

One object of my invention is to provide 10 a ball of the general type referred to in which the stem of the inflating valve is combined with the casing in a novel manner that eliminates the possibility of the terminal portion of said valve stem becoming arranged in such a position that it is difficult 15 to connect the pump to same when the bladder is deflated.

Another object is to provide a ball of the kind referred to that is inexpensive to manufacture and of such design that the bladder can be easily connected to or disconnected from the casing. Other objects and desirable features of my invention will be hereinafter pointed out.

25 Figure 1 is a top plan view of a portion of a foot ball or basket ball constructed in accordance with my invention.

Figure 2 is a bottom plan view of the parts shown in Figure 1, or, in other words, is 30 a view of the inside of the casing with the flap turned back and with the valve stem shown in section, the bladder being omitted.

Figure 3 is a longitudinal sectional view, taken on the line 3—3 of Figure 1.

35 Figure 4 is a transverse sectional view, taken on the line 4—4 of Figure 1; and

Figure 5 is a detail sectional view, illustrating a slight modification of my invention.

40 Referring to the drawings which illustrate the preferred form of my invention, A designates the outer casing of a foot ball, basket ball, punching bag or similar device, B designates the bladder that is arranged 45 inside of said casing, C designates the slit in the casing through which the bladder is inserted, D designates the lacing that normally closes said slit and E designates the flap inside of the casing that is normally 50 arranged over the lacing so as to prevent said lacing from rubbing against the bladder.

The bladder B is equipped with an inflating valve that comprises a metallic valve

stem 1 which is combined with the casing A 55 in such a manner that an inflating pump can be connected to the terminal portion of said valve stem without disturbing the lacing, the casing being provided with a hole 2 arranged at one side of the slit C so as to enable a connection on the end of the hose of the inflating pump to be inserted in said opening and screwed into the terminal portion of the valve stem 1. The hole 2 in the casing is normally closed by a cap 3 that 65 is screwed into the outer end of the valve stem and said valve stem is combined with the casing in such a manner that the outer end of said stem terminates inside of the casing. It is immaterial, however, so far as 70 my broad idea is concerned, whether the outer end of the valve stem 1 terminates inside of the casing or projects slightly into the hole 2 in the casing, but it is preferable to have the valve stem terminate at a point 75 inside of the casing so that the cap or closure 3 for the valve stem will extend flush or substantially so with the outer surface of the casing A.

The novel feature of my improved ball 80 consists in the means that is used for connecting the valve stem 1 of the bladder to the casing, said means being so constructed and arranged that it holds the terminal portion of the valve stem in or in alignment with 85 the hole 2 in the casing, even when the bladder is deflated. Said means also has the added advantage that it is inexpensive to construct and is of such design that the bladder can easily be connected to or disconnected from the casing A of the ball. Briefly 90 stated, said means consists of a nut or other internally screw-threaded device 4 arranged in a pocket on the inner side of the casing A and adapted to have an externally screw-threaded portion on the outer end of the valve stem 1 screwed into same. The pocket which receives and holds the device 4 is formed preferably by one of the stays 5 on the inside of the casing that extends along 100 one side of the slit C and a pocket member 6 that is secured by stitches or in any other suitable manner to the underside of said stay at a point in proximity to the hole 2 in the casing.

105 In the form of my invention shown in Figures 1 to 4 the pocket that receives the device 4 into which the valve stem 1 is screwed

2
is open at one side or edge so that the device 4 can be easily introduced into and removed from said pocket, this form of pocket being desirable, in that it enables the device 4 to

5 be renewed easily in the event the screw threads of said device become stripped or otherwise injured. The top and bottom walls of the pocket that receive the device 4 are provided with holes arranged in alignment

10 with the hole 2 in the casing A and the flap E on the inside of the casing is also provided with an aligned hole 2^a through which the valve stem passes, the method of combining the bladder B with the casing A of the ball

15 being to fold the flap E against the pocket member 6 after the bladder has been introduced into the casing and then insert the valve stem 1 through the hole 2^a in the flap and screw the externally-threaded portion of

20 said stem into the device 4 arranged in said pocket by rotating the valve stem and the bladder to which said stem is connected. Thereafter, the lacing D can be arranged in the lacing holes provided for same in the cas-

25 ing and tightened, because the hole 2 in the casing permits the pump to be connected with the valve stem after the lacing D has been drawn taut so as to close the slit C in the casing.

30 The nut or device 4 that co-operates with the valve stem 1 to connect the bladder with the casing and hold the terminal portion of said valve casing in alignment with the hole 2 in the casing, even when the bladder is de-
35 flated, is mounted in the pocket in such a manner that it cannot rotate during the operation of screwing the valve stem into same. In the form of my invention shown in Figures 1 to 4 the pocket formed by the stay and

40 the pocket member 6 is made considerably larger than the nut 4 so as to enable said nut to be easily introduced into or removed from said pocket, and said nut is provided at one end with a reduced portion 4^a, as shown in

45 broken lines in Figures 1 and 2, that is positioned between two of the lacing holes in the casing so that if said nut starts to turn during the operation of screwing the valve stem into same, the reduced portion 4^a of

50 said nut will strike against the lacing D, and thus be held against further rotation. Obviously, the nut 4 could be formed in various other ways to accomplish this result, such, for example, as having the walls of the

55 pocket conform to the shape of the nut, or providing one wall of the pocket with an abutment to prevent rotary movement of the nut. In the form of my invention illustrated in Figure 5 the stay 5^a on the inside of the

60 casing is provided with a hole or recess that conforms to the outline of a non-circular-shaped nut or internally screw-threaded device 40^a, and said device is held in said recess by means of a member 6^a that is con-

65 nected in any suitable manner to the stay 5^a,

said member 6^a of course being provided with a hole that is in alignment with the internally screw-threaded hole in the device 40^a.

A ball of the construction above described 70 is inexpensive to manufacture; it is of such design that the bladder can be easily connected to or disconnected from the casing; the bladder can be inflated without disturbing the lacing D that closes the slit C in the 75 casing; and deflation of the bladder will not result in the valve stem 1 dropping inwardly into the casing or becoming arranged in such a position that it is difficult to connect the inflating pump to said valve stem, this being 80 due to the fact that the terminal portion of the valve stem is screwed into a nut or other similar device which is arranged in a pocket on the inner side of the casing. The above 85 desirable features, coupled with the fact that the nut 4 can be renewed easily in the event the threads of same become defective, make my ball a decided improvement on the balls of this general type that are now in use.

Having thus described my invention, what 90 I claim as new and desire to secure by Letters Patent is:

1. A foot ball, basket ball or the like, comprising a bladder provided with a valve stem, a casing provided with a slit or opening through which said bladder is introduced into the casing, a pocket on the inner side of said casing arranged at one side of said slit and having a side opening presented towards said slit, a nut or internally screw-threaded device removably mounted in said pocket and adapted to have the terminal portion of said valve stem screwed into same, and a hole in the casing arranged in alignment with said valve stem. 95 100 105

2. A foot ball, basket ball or the like, comprising a bladder provided with a valve stem, a casing provided with a slit or opening through which said bladder is introduced into the casing, a lacing for closing said slit, 110 a pocket on the interior of the casing arranged at one side of said slit and formed by a flexible member attached to the casing, a removable nut or internally screw-threaded device in said pocket adapted to have the terminal portion of the valve screwed into same, said nut being loosely mounted in said pocket and arranged so that a portion of said nut co-operates with said lacing to hold the nut against rotary movement during the 115 operation of screwing the valve stem into same, and a hole in the casing for permitting a pump to be connected to said valve stem. 120

3. A foot ball, basket ball or the like, comprising a bladder provided with a valve 125 stem, a casing provided with a slit or opening through which the bladder is introduced into the casing, a stay on the inner side of the casing that extends along the side of said slit, a member connected to said stay and ar- 130

- ranged in opposed relation to same so as to form a pocket, a threaded device removably mounted in said pocket into which the terminal portion of said valve stem is screwed, 5 and a hole in the casing arranged in alignment with said valve stem.
4. A foot ball, basket ball or the like, comprising a bladder provided with a valve stem, a casing provided with a slit through 10 which the bladder is introduced into the casing, a flap on the interior of the casing that is normally arranged over said slit, a hole in said flap through which the valve stem on the bladder passes, a nut or internally screw-threaded device arranged between said flap and the casing and adapted to have the terminal portion of said stem screwed into same, and a hole in the casing for enabling
- an inflating device to be connected to said valve stem. 20
5. A foot ball, basket ball or the like, comprising a bladder provided with a valve stem, a casing provided with a slit through which the bladder is introduced into the casing, a flap on the inner side of the casing that normally extends over said slit, a lacing for closing said slit, a member connected to the inner side of the casing and arranged between the casing and said flap so as to form a pocket which is open at one side, a nut 30 removably mounted in said pocket and adapted to have the terminal portion of said valve stem screwed into same, and a hole in the casing for enabling an inflating device to be connected to said valve stem. 25

MASON SCUDDER.
